[57] CLAIM

The ornamental design for a winding machine pneumatic retrofit head, as shown and described.

DESCRIPTION

FIG. 1 is a perspective view of a winding machine pneumatic retrofit head showing our new design; FIG. 2 is a perspective view showing the winding machine pneumatic retrofit head in an operating position, the broken line showing of a winding machine pneumatic retrofit head and portions of a winding machine are for illustrative purposes only and forms no part of the claimed design;

FIG. 3 is a left side view of the winding machine pneumatic retrofit head;

FIG. 4 is a top plan view thereof;

FIG. 5 is a front elevational view thereof;

FIG. 6 is a right side view thereof;

FIG. 7 is a bottom plan view thereof; and,

FIG. 8 is a rear elevational view thereof.

The cord member of the drawing has been shown broken away for ease of illustration.

FIG. 1
